CABINET FOR ELECTRICAL COMPONENTS OR THE LIKE

Paul M. Platzman, Brookville, N.Y. (§ Ultrasonic Industries, Inc., 141 Albertson Ave., Albertson, N.Y.)

Filed July 5, 1960, Ser. No. 61,215

Term of patent 14 years

(Cl. D26—5)

Fig. 1.

Fig. 2.

Fig. 3.

Fig. 4.

FIG. 1 is a perspective view of a cabinet for electrical components or the like, showing my new design;
FIG. 2 is a reduced front elevational view;
FIG. 3 is a reduced side elevational view; and
FIG. 4 is a reduced top plan view thereof.

I claim:

The ornamental design for a cabinet for electrical components or the like, as shown.
